UNITED STATES PATENT OFFICE

WILLIAM C. HEDGCOCK, OF CHICAGO, ILLINOIS, ASSIGNOR TO AMERICAN STEEL
FOUNDRIES, OF CHICAGO, ILLINOIS, A CORPORATION OF NEW JERSEY

CAR TRUCK

Application filed August 15, 1927, Serial No. 212,914. Renewed June 10, 1930.

My invention relates to an improved railway car truck assembly, and particularly to the type of truck in which a spring cap and the bolster ends are mounted between the columns of the side frame for vertical movement and where means are provided for limited movement of said bolster transverse to and relative to the car truck.

My invention is an improvement on the type of truck assembly disclosed in the patent issued to G. S. Chiles No. 1,582,901 on May 4th, 1926, and my invention has for its principal object, the provision in a truck of this type of flat bearing surfaces on the opposed inter-faces of the columns of the truck for cooperation with flat side faces of the bolster ends, and for grooved portions on the inter-opposed faces of the columns at their lower portions for cooperation with the spring cap, to serve in the capacity of a vertical guideway.

Another object of my invention is to eliminate the stepped bearing surfaces on the opposed inter-faces of the vertical columns at their portions which cooperate with the sides of the bolster, whereby the necessity for very accurate casting to assure proper bearing fit on the various stepped surfaces is eliminated; and to provide an uninterrupted flat bearing surface at this location, together with other means for limiting the transverse movement of the bolster.

These and other objects are accomplished by means of the arrangement disclosed in the accompanying sheets of drawings, in which—

Figure 1 is a fragmentary side elevation of the truck side frame, springs and spring cap, and bolster ends all constructed in accordance with my invention.

Figure 2 is a plan view of Figure 1, and Figure 3 is a cross-sectional view of the device taken on the line 3—3 of Figure 1, and looking in the direction of the arrows.

The various novel features of the invention will be apparent from the following description and drawings and will be particularly pointed out in the appended claims.

Referring to the drawings, it will be noted that my invention is shown applied to a truck which embodies a side frame 10, having the

compression member 11 and the tension member 12 connected at their intermediate portions by the vertical columns 13 and 14. The upper surfaces of the tension member 12 between the columns is constructed to form a 55 spring seat 15 having the steps 16 and 17 at the ends thereof, the spring seat having mounted thereon, the coil springs 18 and 19 in the same manner as disclosed in the patent above referred to. Mounted on the upper 60 end of the spring is the spring cap 20, the under-surface of which is of a stepped formation so as to contact and properly rest upon the upper surfaces of the coil springs 18 and 19. 65

Referring to Figure 3, it will be noted that the spring cap 20 is provided on its upper surface with a plurality of elongated grooves 21 having arcuate bearing surfaces 22 adapted to receive the anti-friction rollers 70 23. The outer ends of the bolster 25 are positioned between the vertical columns 13 and 14 of the side frame and are provided at their under-surface with complementary grooves 26 having arcuate bearing surfaces 75 27 for supporting the bolster by anti-friction engagement with the rollers 23. The structure thus far described is similar to that disclosed in the patent above referred to and constitutes merely the form of truck in connection with which I have shown my invention, it being understood that my invention may be applied to any type of truck in which movement of the bolster positioned between the vertical columns is provided transverse 80 85 to the truck and relative to the spring cap and other parts of the truck.

My invention relates to the formation of the vertical columns 13 and 14 at their inter-opposed faces where I provide at the upper 90 portions, flat bearing surfaces 28 and 29 which cooperate with the flat side faces 30 and 31 at the bolster ends. The lower portion of the inter-opposed faces of the columns are grooved centrally as at 32 and 33 in a manner to form stepped surfaces and for cooperation with the lugs 34 and 35 on the ends of the spring cap 20. The lugs are of such dimensions that they occupy substantially the entire width of the groove whereby they are 95 100

held against movement transverse to the truck, but are free to move vertically in the grooves 32 and 33 acting as guideways by virtue of the elongated nature of the grooves. Provided on the bolster preferably on its upper surface are upstanding lugs 36 which are, when in their normal position, spaced from the inter-surface of the compression member of the side frames and which form stops for engagement with the side frame for limiting the transverse movement of the bolster. It is to be understood that these lugs may be placed on the bolster in any desired position for cooperation with the side frame for limiting the transverse movement.

In practice, it will be noted that I have provided a truck in which the bolster is free to move transversely of the truck a limited amount while being firmly held against movement longitudinally of the truck by means of the bearing surfaces 28 and 29 which closely engage the surfaces 30 and 31 on the sides of the bolster ends.

It will be further noted that in such a device that I have provided, uninterrupted flat bearing surfaces at the sides of the bolster which form simplified means for assuring bearing contact throughout the entire bearing surface and which assume a reduction in wear and trouble at this point. In addition, I have provided a vertical guideway for preventing transverse movement of the spring cap while permitting vertical reciprocation thereof under the action of the springs when the truck is in use. The lugs 36 serve in the capacity of stops for limiting the transverse movement of the bolster and they are initially placed in such position that they will contact the side frame after the amount of movement of the bolster which is desired has taken place.

I have eliminated in my device, the necessity of accurately casting the bolster ends and the side frames to assure proper bearing fit throughout the entire surface which is necessary in the type of device shown in the patent above referred to, and the trouble which is encountered when such parts are not accurately fitted in service. This structure makes for a greatly improved device of simplified construction and one which is considerably cheaper in that the extreme care in casting is eliminated, together with the additional labor necessary to make proper fits from the castings.

I claim:

1. An integral side frame casting comprising, a compression member, a tension member and columns connecting said members, each column extending upwardly and inwardly from said tension member and thence vertically upwardly, the vertical portions of each of said columns having a groove in their opposed faces providing stepped guiding sur-

faces adapted to cooperate with a spring cap and a flat uninterrupted bearing face adapted to cooperate with a bolster.

2. In a railway car truck, a side frame having a compression member, a tension member, 70 columns connecting said members, said columns extending upwardly and inwardly from said tension member and thence vertically upwardly, the lower portion of said columns providing a spring cavity, springs in said 75 spring cavity, the vertical upper portion of each of said columns having a groove in their opposed faces and a flat uninterrupted bearing face located adjacent said groove, a spring cap and bolster supported on said 80 springs and located between the vertical upper portion of the columns, said grooves forming stepped guiding surfaces for cooperating with the spring cap, and said flat bearing faces adapted to have contacting engagement with flat bearing surfaces on said 85 bolster, the entire bearing portions of said bolster being of a width less than the distance between columns.

3. In a truck, the combination of a side frame including tension and compression members and spaced columns integral therewith, said columns having bolster guides and spring cap guides, springs mounted on said tension member, a spring cap for said springs 90 having portions cooperating with said spring cap guides, and a bolster embraced by said guides and having bolster guide cooperating portions, said bolster being supported by said spring cap and provided with an upstanding 95 lug adapted to contact said frame for limiting transverse movement of said bolster.

Signed at Chicago, Illinois, this 5th day of July, 1927.

WILLIAM C. HEDGCOCK.
